DESIGN FOR A BALL COCK

Alfred C. Arbogast, Elkhart, Ind., assignor to Northern Indiana Brass Company, Elkhart,
Ind., a corporation of Indiana

Application December 11, 1939, Serial No. 88,829

Term of patent 14 years

To all whom it may concern:

Be it known that I, Alfred C. Arbogast, a citizen of the United States, residing at Elkhart, in the county of Elkhart and State of Indiana, have invented a new, original, and ornamental Design for Ball Cocks, of which the following is a specification, reference being had to the accompanying drawing, forming part thereof, in which:

Fig. 1 is a side elevation,

Fig. 2 is an elevation partially broken away looking from the left of Fig. 1, and

Fig. 3 is a top plan view of a ball cock, showing my new design.

I claim:

The ornamental design for a ball cock, as shown.
